UNITED STATES PATENT OFFICE.

SAMUEL B. HOOD, OF MINNEAPOLIS, MINNESOTA, ASSIGNOR TO LINE MATERIAL COMPANY, OF SOUTH MILWAUKEE, WISCONSIN, A CORPORATION OF WISCONSIN.

CIRCUIT MAKING AND BREAKING DEVICE.

Application filed July 31, 1924. Serial No. 729,306.

This invention relates to certain new and useful improvements in circuit making and breaking devices and refers more particularly to an electrical switch in which a liquid medium, such as mercury or the like, is employed.

Heretofore, circuit making and breaking devices utilizing a liquid contactor have had the electrodes or stationary contacts projected into the mercury or other liquid to make the circuit, and vice versa, which has proven objectionable, as the arcing, incidental to the breaking of the circuit, gradually consumes the electrodes or contacts.

Having the above and other objections in mind, this invention contemplates as one of its objects the provision of a circuit making and breaking device of the character described wherein the circuit is made and broken between the body of mercury or other medium and not by projecting the electrodes thereinto.

It is another object of this invention to provide a circuit making and breaking device of the character described wherein the clinging or stretching characteristic of mercury is utilized to procure the quick breaking of the circuit in which the device is included.

This invention contemplates as another object the provision of a circuit making and breaking device in which a new contact surface is provided each operation and in which the movable contact is maintained in a clean condition by reason of the quick movement thereof under operation.

A further object of this invention resides in the provision of a circuit making and breaking device of the character described in which the electrodes or stationary contacts are of a relatively large area whereby an increased displacement capacity is obtained and consequently the volume of mercury necessary is reduced to a minimum.

This invention contemplates as a further object the provision of a device of the character described having means for conveniently adjusting the stationary contacts or electrodes to regulate the normal level of the mercury or other medium.

It is a further object of this invention to provide a device of the character described which is operable to make the electric circuit in which the same is included upon the displacement of the mercury or other liquid.

And a still further object of this invention resides in the provision of a device of the character described having provision for its manipulation from a distant station and which is of compact design to permit its location in any convenient place.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated two complete examples of the physical embodiment of my invention constructed according to the best modes I have so far devised for the practical application of the principles thereof, and in which:

Figure 1 is a view of a contact making and breaking device embodying the features of my invention, the same being partly in vertical section and partly in side elevation;

Figure 2 is a view, partly in section and partly in elevation, taken through Figure 1 on the plane of the line 2—2;

Figure 3 is a view, partly in section and partly in top plan, taken through Figure 1 on the plane of the line 3—3;

Figure 4 is a fragmentary detail view, partly in section and partly in elevation, taken through Figure 3 on the plane of the line 4—4; and

Figure 5 is a view similar to Figure 4 of a slightly modified type of my invention.

Referring now more particularly to the accompanying drawings, in which like numerals designate like parts throughout the several views, the numeral 10 designates a base member of porcelain, or other suitable non-conducting material, having a central well or chamber 11 therein and outer wells or chambers 12 and 13. The wells are preferably cylindrical for convenience in forming the base, the central well being of greater diameter than the outer wells. The partition walls 14 separating the wells are slotted or cut away from a point spaced from the bottom of the wells to form connecting passages or openings 15, as best illustrated in Figures 1 and 5, and the upper edges of the walls are inclined inwardly and downwardly toward

the central well, as illustrated in Figures 1 and 2, for the reasons hereinafter described.

The upper end of each outer well is closed by a contact plate 16 of brass, or any other

6 suitable conducting material, secured to the base 10 by a screw or other fastening member 17, which also provides a terminal to which one end of a conductor or line 18 of the circuit in which the device is included, is 10 connected. Each contact plate 16 is provided with a threaded opening 19 in axial alignment with its well and through which a contact stud 20 is threaded with its lower end extended into the well to be immersed in the 15 mercury or other liquid M which substantially fills the wells approximately to the level of the passages 15. The contact studs are preferably of relatively large diameters to give them increased displacement values 20 and thus reduce the volume of liquid necessary for the device.

25 Mounted on the base 10, over the well 11 with its tubular core 21 in axial alignment therewith, is a solenoid 22 into which an armature 23 is movable. In that form of my invention illustrated in Figures 1 to 4, the armature 23 is preferably formed of an iron wire core 24 molded in "bakelite", or any other suitable material, and has its lower 30 end disposed in the well 11 and enlarged to form a displacing plunger 25.

35 The wells 11, 12 and 13 are normally filled with mercury or any other suitable liquid as before described, the normal level of which is slightly lower than the upper edges 26 of the partition walls 14, but preferably with the lower ends of the contact studs 20 immersed therein, as a result of which the continuity of the circuit through the conductor or line 18 is 40 broken between the body of liquid M at the partition walls 14 and not at any of the contacts. The weight of the armature 23 and its plunger 25 is such that it normally sinks to the bottom of the central well and 45 places the mercury or other liquid therein raising its level to join the liquid in the wells into a single body through the passages 15, as a result of which the contacts 20 are bridged and the circuit completed 50 through the body of the liquid M.

55 When it is desired to break the continuity of the circuit, the solenoid 22 is energized by being connected with a source of electrical current, as a result of which the armature 23, which is normally disposed below the center of the magnetic force thereof, is quickly moved into the tubular core 21 withdrawing the plunger 25 from the body of mercury M, permitting the displaced mercury to return 60 to the central well or chamber. The upward movement of the core and plunger under the magnetic influence of the solenoid 22 is arrested by a cushion spring 27 preferably of the spiral, conical type wound about the core 65 23 and normally resting on the plunger 25,

The cushion spring is compressed between the plunger and the lower flange 28 of the solenoid spool when the armature is drawn thereinto.

Upon withdrawal of the plunger 25 in the manner above described, the displaced mercury returns to the central well or chamber and by reason of its stretching or clinging characteristic, holds together over the edges 26 of the partition walls until the tension thereon increases to a predetermined degree, when it breaks or separates at the edges 26 with a snap, producing a quick break in the continuity of the circuit. The inclination of the upper end or edges of the partition walls also facilitates the quick separation of the mercury. This characteristic of the mercury also permits the normal level of the mercury, when the solenoid 22 is energized to withdraw the plunger from the mercury, 85 to be below the edges 26.

90 This type of contact making and breaking device is designed to maintain the continuity of the line 18 in the event for any reason the control circuit, not shown, of the solenoid 22 fails. This is especially useful for street lighting systems where it is desired to have the lights lit during the day in the event of failure of the control circuit rather than extinguished at night.

95 In that form of my invention depicted in Figure 5, an inverse arrangement is illustrated wherein energization of the solenoid 22 makes the circuit and the deenergization thereof breaks the continuity of the circuit. This is accomplished by constructing the armature 23 and the plunger 25 of a tubular and light construction so that the overall mass is sufficiently light to permit the plunger to normally float with the armature 100 23 above the center of magnetic force of the solenoid. In this form, energization of the solenoid 22 draws the armature 23 downwardly to tend to center its metal with respect to the center of magnetic force, forcing the plunger 25 into the body of mercury 105 which overflows over the walls 14 through the passages 15 to make the circuit. As the operation of this type of device, with the exception of that above described, is the same 110 as that of the one illustrated in Figures 1 to 4, further description thereof is deemed unnecessary.

115 From the foregoing description taken in connection with the accompanying drawing 120 it will be readily evident to those skilled in the art to which an invention of this character appertains that I provide an improved contact making and breaking device which is of very compact construction, which eliminates the arcing due to the breaking of the current, which may be controlled at any distant point, which break the circuit by separation of the liquid contact thus affording a new contacting surface each operation and 125 130

eliminating injury to the contacts by the destructive arcing incidental to the breaking of an electrical circuit, and one in which the agitation of the liquid by the movement of the displacing member produces a cleansing of the mercury.

What I claim as my invention is:

1. An appliance of the character described, comprising a base member of insulating material, a central chamber formed in the base member, outer chambers formed in the base member, the upper portions of the partition walls separating the chambers being cut away to provide passages connecting the chambers, a liquid in the chambers, the liquid in the chambers being normally separated by the partition walls, contact plates closing the upper ends of the outer chambers, contact studs threaded in the contact plates and passed into the outer chambers, and means adapted to displace the liquid in the central chamber to raise the level thereof above the passages in the partition walls to join with the liquid in the outer chambers and electrically bridge the contact studs. 70
2. An appliance of the character described, comprising a base member of insulating material, a central chamber formed in the base member, outer chambers formed in the base member, the upper portions of the partition walls separating the chambers being cut away to provide passages connecting the chambers, a liquid in the chambers, the liquid in the chambers being normally separated by the partition walls, contact plates closing the upper ends of the outer chambers, contact studs threaded in the contact plates and passed into the outer chambers, said contact studs being of a diameter sufficient to substantially fill the outer wells to increase their displacement capacity, and means adapted to displace the liquid in the central chamber to raise the level thereof above the passages in the partition walls to join with the liquid in the outer chambers and electrically bridge the contact studs. 75
3. An appliance of the character described, comprising a base member of insulating material, a central chamber formed in the base member, outer chambers formed in the base member, the upper portions of the partition walls separating the chambers being cut away to provide passages connecting the chambers, a liquid in the chambers, the liquid in the chambers being normally separated by the partition walls, contact plates closing the upper ends of the outer chambers, contact studs threaded in the contact plates and passed into the outer chambers, and means adapted to displace the liquid in the central chamber to raise the level thereof above the passages in the partition walls to join with the liquid in the outer chambers and electrically bridge the contact studs, the upper edges of the partition walls being inclined downwardly and inwardly toward the central chamber to provide a relatively narrow edge over which the liquid separates upon withdrawal of the displacing means to thus disconnect the contact studs. 80
4. An appliance of the character described, comprising a chamber, mercury in said chamber, an electrical circuit, contacts in said circuit and adapted to be electrically bridged to complete the circuit by the mercury upon raising of its level a predetermined degree, means operable to displace the mercury and raise the level thereof, and means operable to adjust the normal level of the mercury. 85
5. An appliance of the character described, comprising a chamber, mercury in said chamber, an electrical circuit, a contact included in the electrical circuit and normally immersed in the mercury, said circuit being made and broken by the raising and lowering of the mercury, means operable to displace the mercury and raise the level thereof beyond normal, and means for adjusting the degree the contact is immersed in the mercury whereby the mercury normal level may be adjusted. 90
6. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact studs adapted to be partly submersed in the mercury, at all times, and means whereby the normal level of the mercury may be adjusted by the degree the contacts are projected into the mercury. 95
7. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 100
8. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 105
9. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 110
10. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 115
11. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 120
12. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 125
13. An appliance of the character described, comprising a base member, a central chamber formed in the base member, outer chambers formed in the base member, mercury in the chambers and normally divided into separate bodies by the dividing walls of the chambers, an electrical circuit, contacts projected into the mercury and included in the circuit and adapted to be electrically bridged to complete the circuit by raising of the mercury level to join the several bodies, means operable to displace the mercury and raise the level thereof, contact plates covering the outer chambers, and contact studs adapted to be partly submersed in the mercury, at all times, and having a threaded engagement with the contact plates whereby the normal level of the mercury may be adjusted by the degree the contacts are projected into the mercury. 130

8. An appliance of the character described, comprising a base member, a central chamber formed in the base member, outer chambers formed in the base member, mercury in the chambers, an electrical circuit, contacts included in the circuit and adapted to be electrically bridged to complete the circuit upon raising of the mercury level a pre-
determined degree, a solenoid positioned above the central chamber, a displacement member of insulating material, and an armature embedded in the displacement member and adapted to be attracted by the solenoid. In testimony whereof I affix my signature.

SAMUEL B. HOOD.
